UNITED STATES PATENT OFFICE.

EDWARD W. DRECKSCHMIDT, OF ST. LOUIS, MISSOURI.

CHEMICAL FIRE APPARATUS.

1,259,610.

Specification of Letters Patent. Patented Mar. 19, 1918.

Application filed July 27, 1914. Serial No. 853,330.

To all whom it may concern:

Be it known that I, EDWARD W. DRECKSCHMIDT, a citizen of the United States, residing at the city of St. Louis and State of Missouri, have invented a new and useful Chemical Fire Apparatus, of which the following is a specification.

This invention relates to chemical fire apparatus, and consists in the novel design, arrangement and combination of parts herein-after specified and claimed.

An object of the invention is to provide an efficient apparatus from which a fire extinguishing fluid will be ejected by means of a gas generated by the mixing of suitable chemicals, said gas-forming chemicals being normally contained in separate compartments which are adapted to be communicated by operation of a plunger which destroys the partition wall separating the chemicals and permitting the same to mix for the purpose of forming the gas.

Another object of the invention is to provide separate containers for the gas-forming chemicals whereby the same will be protected from the fire extinguishing liquid and prevented from mixing with each other until the partitions separating the chemical compartments is broken by operation of a plunger for operating the apparatus.

Other valuable features and advantages will be apparent from the following detailed disclosure taken in connection with the accompanying drawing, in which—

Figure 1 is a side elevation partially in section of the complete apparatus embodying my invention.

Fig. 2 is a cross section taken substantially on the line 2—2 of Fig. 1, illustrating in further detail certain of the elements of the present invention.

Fig. 3 is a cross section substantially on the line 3—3 of Fig. 1 illustrating certain details of construction; and

Fig. 4 is a vertical section illustrating in detail the separate gas generating chemical compartments, the parts being separated more clearly to show the manner in which they are assembled.

In the embodiment of the invention illustrated in the drawing I have shown a tank or container 1 which is made of spun metal, or other suitable material and which is adapted to contain the fire extinguishing liquid.

The tank or container 1 is provided at its

lower end with a discharge spigot 2 from which the liquid contained therein is forced in a manner that will be hereinafter more fully explained. The size or shape of the tank or container 1 is not material and it will be understood that a container to accommodate any desired quantity may be provided.

The tank or container 1 is provided with a removable closure 3 which has threaded engagement with the neck of the closure as indicated at 4. A rubber gasket 5 is provided to seal the joint between the cap or closure 3 and the container so as to prevent the spilling of the liquid contained in the tank, and also prevent deterioration of the chemical solution, used as an extinguishing liquid, by the atmosphere. The closure 3 is also provided with a polygonal boss 6 which may be engaged by a wrench for securely seating the same upon the neck of the tank or container 1. A plunger 7 is mounted in an axial opening in said closure 3, said plunger being held in raised position by an extension spring 8 encircling the stem thereof.

A series of inwardly projecting lugs 9 are provided on the inner walls of the tank or container 1 and are disposed at a considerable distance below the neck of the container, as clearly indicated in Fig. 1 of the drawing. These lugs 9 provide means for supporting the gas generating chemical containers.

For the purpose of generating a gas for driving the fire extinguishing liquid from the container through the spigot 2 a quantity of carbonate of soda may be mixed with a quantity of hydrochloric acid, or, if desired, other chemicals may be utilized for a similar purpose.

In order to isolate the gas generating chemicals from each other and also from the fire extinguishing liquid I provide separate containers for the component gas generating chemicals, said containers being immersed in the fire extinguishing liquid within the tank. It is an object of the present invention to provide for the complete isolation of the various chemicals until it is desired to force the fire extinguishing liquid from the container 1.

As illustrated in the drawing, I have shown a cylindrical acid container 10 which is provided with a constricted threaded neck 11 and a container 12 which is in the form of an open cylinder is provided for the car-

bonate of soda or similar chemical. The container 12 is provided at its lower end with an internally threaded bell 13, thus providing means for connecting the two containers by threaded engagement.

5 A partition wall 14 composed of mica, or similar fragile and readily breakable material, is interposed between the container 10 and the container 12. Encircling the partition 14 and superimposed thereon is a rubber gasket 15 which, with the partition 14, is adapted to provide a sealed closure between the two containers.

10 The container 12 is provided at its upper end with a closure 16 composed of like material as is utilized for the partition 14. The closure 16 is held in place by a cap 17 in the form of an annular ring which is provided with threaded flanges adapted to be 15 screwed on to the upper threaded end of the container 12. In order to form a sealed joint between the cap 17 and the container 12, I provide rubber gaskets 18 which are supported by an annular flange 19 formed 20 on the exterior wall of the container 12.

25 The carbonate of soda or like chemical is contained in a capsule 20 formed from telescoping sections composed of wire gauze, or other reticulated material.

30 A serrated ring 21 formed integral with the exterior wall of the container 12 provides means for supporting the gas generating chemical containers within the tank or container 12. The support proper for the 35 gas generating chemical containers comprises a cage or supporting frame, including a ring 22 and a suspended disk 23, said disk being supported below the bottom of the container 10 by means of a plurality of 40 tie rods 24, supported at one end by said ring 22.

45 A cage or supporting frame thus formed provides a reinforcement for the containers. When the containers are formed of glass or other breakable material and the tank should be accidentally tilted, the walls of the containers are prevented from striking against the walls of the tank and becoming accidentally broken. It is not at all essential 50 that the cage or supporting frame be used in all instances, but the serrated ring 21 may be seated directly on the lugs 9 and the cage or supporting frame be dispensed with. It is preferred, however, to include 55 the frame for the reasons mentioned. It will be noted that when said ring 22 is seated on the lugs 9 and the containers 10 and 12 lowered into position that the bottom of the container 10 will rest upon the disk 23 and 60 that the serrated ring 21 formed on the upper container will rest upon the ring 22. The gas generating chemical containers are thus in position so that when the plunger 7 is depressed the closure 16 will be broken 65 through and the capsule containing one of

the gas generating chemicals will be forced downwardly through the partition 14 and will be immersed in the liquid in the lower container. As both the closure 16 and the partition 14 are broken in this operation, the 70 gas generated within the container 10 will pass outwardly through the open end of the container 12 upon the liquid in the tank 1, thereby forcing the same from the spigot 2, the pressure depending upon the amount 75 of the gas generated by the mixing of the gas generated chemicals.

75 In practice it is essential that the containers 10 and 12 shall be formed of material which is free from corrosion or deterioration from the chemicals surrounding them, or contained therein. I, therefore, prefer to construct these parts of glass or other material that is entirely free from chemical action.

80 The construction which I have provided also permits the ready recharge of the apparatus after the contents has been expelled therefrom, it being only necessary to provide additional chemicals and to replace the 85 partition 14 and the closure 16.

85 It will also be noted that the several parts may be readily assembled and placed in proper position for future operation in recharging the apparatus.

90 I am aware that numerous modifications in details of construction may be made without departing from the spirit and scope of the invention, and I do not limit myself, therefore, to the exact disclosure but what 95 I claim and desire to secure by Letters Patent is:—

95 1. A chemical fire apparatus, comprising a tank, a plunger operatively mounted at the upper end of said tank, two noncommunicating containers in said tank in alignment with said plunger, a device in said tank for supporting said containers centrally therein, a detachable and replaceable frangible closure for one of said containers, 100 and a detachable and replaceable frangible partition between said containers, and a reticulated chemical capsule supported by said partition, said closure being adapted to be broken upon the depression of said 105 plunger, and said capsule being adapted to be forced through said partition upon the depression of said plunger, whereby the contents of the capsule are brought into 110 contact with the material in the lower container to form a gas whereby the liquid in the tank is expelled from the tank, said closure and partition being removable after 115 being broken and replaceable by unbroken ones in connection with the same containers 120 after an operation and use of the apparatus.

125 2. In a chemical fire apparatus, the combination with a fire extinguishing liquid tank, of a pair of chemical containers supported therein, one of said containers being 130

- in the form of a jar having one open end, and the other being in the form of a chamber having both ends open and secured to the open end of the first-named container, 5 a removable and replaceable frangible closure constituting a partition between said containers, a removable and replaceable frangible closure for closing communication between the second-named container and the 10 tank, and means for breaking said closures whereby the contents of said containers will be mingled and the gas escaping therefrom will be permitted to escape upon the liquid in said tank.
- 15 3. In a chemical fire apparatus, a tank adapted to contain a fire extinguishing liquid, an outlet spigot at one end of said tank, a removable closure for the opposite end of said tank, a plunger operatively 20 mounted in said closure, an acid container within said tank and having an open end, a second container in connection with said acid container, a removable and replaceable frangible partition between said two containers, 25 means holding said partition in stationary position between said containers, an impermeably sealed closure for said second container, and means holding said closure in position on said second container, said closure and said partition being adapted to be 30 broken by the depression of said plunger, whereby the contents of said containers are caused to mingle and to establish communication between said containers and the interior of said tank, said closure and partition being removable after being broken and replaceable by unbroken ones in connection with the same containers after an operation and use of the apparatus.
- 40 4. In a chemical fire apparatus, a tank adapted to contain a fire extinguishing liquid, a discharge outlet from said tank, a removable closure for one end of said tank, a spring-suspended plunger operatively 45 mounted in said closure, a liquid-container supported in said tank, a second container supported above the liquid-container, a removable and replaceable frangible partition dividing said containers, a perforated 50 capsule supported by said partition, and a removable and replaceable frangible closure for said second container, said closure being adapted to be broken by the plunger, and the partition being adapted to be broken by 55 the capsule actuated by the plunger, whereby said capsule is forced into said liquid-container and communication is established between the interior of said containers and said tank.
- 60 5. In a chemical fire apparatus, a tank, a plunger operatively mounted in said tank, two non-corrodible non-communicating containers supported in said tank in axial alignment with said plunger, a frangible partition wall removably mounted between the 65
- containers, means for supporting and holding said partition between said containers, a reticulated capsule supported by said partition and containing a chemical, a frangible closure for one of said containers 70 mounted below the inner end of the plunger, and a cap for removably holding said last-named closure in adjustment whereby a sealed joint is effected for said container.
6. In a chemical fire apparatus, the combination with a tank adapted to contain a fire extinguishing liquid, a spigot leading from said tank, a closure for said tank, means for forming a sealed joint between said closure and said tank, a plunger operatively 75 mounted in said closure, a glass container supported in said tank below said plunger, an open-ended cylindrical glass container having threaded engagement with said first glass container and superimposed 80 thereon, a mica partition wall removably mounted between said containers, a reticulated box adapted to be supported by said partition wall and to contain a powdered chemical, a mica closure for said second-named container, a cap in connection with means for holding said closure in adjustment and for sealing the joint between said cap and said container, inwardly projecting 85 lugs on the inner wall of said tank, and an annular supporting flange formed integral 90 with said second-named container adapted in connection with said lugs to support said containers in axial alignment with said plunger, whereby said partition and said closure 95 may be destroyed by the operation of the plunger, substantially as specified.
7. In a chemical fire apparatus, a tank, a removable cap for said tank, a spring operated plunger mounted in said cap, supports 105 on the inner wall of said tank, a duplex container mounted upon said support comprising a lower section in the form of an open-ended glass jar and a cylindrical section having threaded engagement over the open end 110 of said first-named section, a removable partition for the open end of said first-named section, a frangible closure for the other end of said second-named section, a removable cap for holding said last-named closure in 115 adjustment, a reticulated capsule adapted to be mounted in said second-named section and supported by the partition between the two sections, said capsule being adapted to contain a powdered chemical, and a spigot 120 controlling the passage of fluid from said tank.
8. A fire apparatus comprising a tank having an open end, a removable cap for said tank, a spring operated plunger mounted in 125 said cap, a duplex container insertible through the open end of said tank, supports on the walls of said tank engageable with said container for supporting the same in axial alignment with the plunger, a support- 130

ing frame carried by said supports and extending to the lower end of said container, a removable frangible partition dividing said container into two non-communicating 5 chambers, a frangible closure for the upper end of said container, a removable cap for the upper end of said container for holding said closure in position, a sealing gasket between the cap and the container, a removable 10 capsule supported by the partition wall between the chambers, said capsule being adapted to contain a powdered chemical and arranged in axial alinement with the plunger, whereby when said plunger is depressed the upper closure is broken and the capsule forced through the partition between the chambers, and means for controlling the outlet of fluid from said tank.

9. In a chemical fire apparatus, a tank, 20 two non-communicating containers therein adapted to contain two gas forming chemicals, supports extending from the side wall of the tank for supporting said chemical containers, a ring on one of said containers, 25 an additional ring supporting said first-named ring and adapted to be supported by said supports, a plate at the bottom of the other of said containers, and tie-rods extending between said additional ring and 30 said plate whereby said containers are supported centrally within the tank.

10. In a chemical fire apparatus, a tank, a plunger extending through and operatively supported by one wall of said tank, a 35 non-corrodible container adapted to contain a gas forming material supported in said tank in alinement with said plunger, an additional non-corrodible container adapted to contain another gas forming material supported in said tank in alinement with said plunger and the first-named container, a removable and replaceable partition wall between and separating said containers and supporting the gas forming material in the 40 second-named container, means for supporting and holding said partition wall between said containers, and a removable and replaceable frangible closure for the second-named container mounted adjacent to the 45 inner end of the plunger, said closure and said partition wall being adapted to be broken upon the depression of said plunger whereby said gas forming materials are brought together in the lower container to 50 form a gas whereby the liquid in the tank is expelled therefrom, said closure and partition wall being removable after being broken and replaceable by unbroken ones in connection with the same containers after 55 an operation and use of the apparatus.

Copies of this patent may be obtained for five cents each, by addressing the "Commissioner of Patents, Washington, D. C."

11. In a chemical fire apparatus, a tank, a plunger extending through and operatively supported by one of the walls of said tank, a container arranged to contain a gas forming material supported in said tank, a 65 removable and replaceable frangible wall closing the end of said container which is toward said plunger and arranged to support another gas forming material, an additional container arranged to inclose the gas 70 forming material which is supported by said wall, a removable and replaceable frangible closure for the end of said additional container which is toward said plunger, said closure being adapted to be broken 75 upon the depression of said plunger, and a device within said additional container whereby said partition wall will be broken upon the depression of said plunger and the gas forming material in said additional container discharged into the first-named container, said closure and partition wall being removable after being broken and replaceable by unbroken ones in connection with the same containers after an operation of 80 the apparatus.

12. In a chemical fire apparatus, a tank, a plunger extending through and operatively supported by one of the walls of said tank, a container arranged to contain in the bottom 90 thereof a gas forming material supported in said tank in alinement with said plunger, a removable and replaceable frangible partition wall dividing the upper portion of said container from the lower portion thereof and arranged to support another gas forming material, a removable and replaceable frangible closure for the upper end of said container which is adjacent to said plunger adapted to be broken upon the depression of said plunger, and means whereby said partition wall will also be broken upon the depression of said plunger whereby the gas forming material supported by said partition is discharged into the material in 95 the lower portion of the container to form a gas whereby the liquid in the tank is expelled therefrom, said closure and partition wall being removable after being broken and replaceable by unbroken ones in connection with the same containers after an operation of 100 the apparatus.

In witness whereof, I have signed this specification in the presence of two subscribing witnesses.

EDWARD W. DRECKSCHMIDT.
